[57] **ABSTRACT**

A method and apparatus by which physical structures are fabricated substantially entirely of resilient members or modules. The structures may be compressed for shipment and, when released from restraint, spring into the final shape of structure desired.

**METHOD AND APPARATUS FOR FABRICATING
STRUCTURES**

GOVERNMENT INTEREST

The invention described herein may be manufactured and used by or for the Government of the United States of America for government purposes without the payment of any royalties thereon or therefor.

BACKGROUND OF THE INVENTION

The field of self erectable or expandable structures has been dominated in the past by power operated lazy tong structures. The present invention contemplates the fabrication of self erectable structures by means of individual or integral spring sections. Such construction eliminates unnecessary weight and greatly simplifies fabrication. Also, a more uniform application of power is possible.

**BRIEF DESCRIPTION OF THE SEVERAL VIEWS OF THE
DRAWING**

FIG. 1 is a diagrammatic perspective view of a first structure fabricated in accordance with the invention;

FIG. 2 is a section taken along line 2 — 2 of FIG. 1;

FIG. 3 is a longitudinal cross sectional view of the structure of FIG. 1 in packaged form;

FIG. 4 is a fragmentary perspective of a portion of FIG. 2 in enlarged detail;

FIG. 5 is a diagrammatic perspective of a second structure fabricated in accordance with the invention;

FIG. 6 is a view similar to FIG. 5 illustrating the recovery of a vehicle;

FIG. 7 is an enlarged detail view of a portion of FIG. 5 illustrating one manner of assembly of elements; and

FIG. 8 is an exploded sectional view taken along line 8 — 8 of FIG. 7.

DESCRIPTION OF THE INVENTION

In FIG. 1, spring modules 12 are connected in orthogonal rows to form an antenna unit 14, 14' which, in the compressed state, forms a low profile package as shown in FIG. 3, while in the expanded state, assumes an elongated shape in the form of an antenna, for example, as shown in FIGS. 1 and 2.

For convenience in shipping and to form a base for the unit, a container or box 16 may be provided. The container 16 may be of any shape which will accommodate a particular spring device but is here shown as a rectangular box having a bottom 18 and sides 23, 24.

The antenna sections 14, 14' are fastened for movement relative to a fixed coil 40' which may be fastened to container 16 by means of weld 48, for example. Suitable bracing should be provided when the sections are extended and such is indicated here simply by cables 20 fastened to the lowermost spring module 12 and secured to container 16 at points 22.

Uppermost spring module 12 in FIG. 2 has four coils 38, 40, 42 and 44 and as shown has its coil 38 fastened to a coil 44' of a spring module of section 14'. The second spring module from the top in section 14 has its coil 38' fastened to coil 44' of section 14' and so on. The sections may be fastened at these points by any suitable hardware or may be simply welded, as shown in FIG. 4, if the welding is carefully done.

When the unit is packed for shipment with coils 40, 44 fastened by releasable means 50, a suitable lid 34 may be used to enclose the container as shown in FIG. 3. Spring units 12 may be made integral by joining the ends of the spring material between joints as shown at 36 in FIG. 4. Welds 36 are typical but, as stated above, may be displaced by ordinary bolts or other suitable hardware.

FIG. 5 shows a cylindrical spring structure designed to be lowered over an object to ensnare it for retrieval. Spring units 12' are connected by bolting, for example as shown in FIGS. 7 and 8, to form a cylinder. The spring elements are held in

stressed position by a plurality of severable bands 50' for form a cylinder with maximum diameter and minimum height. When bands 50 are severed, the spring units assume a position of released tension tending to form a cylinder of minimum diameter and maximum length as shown in FIG. 6.

As shown, the unit may be transported and lowered by a hoist line 56 attached to a cable 52 threaded through coils 74 of the upper row of spring elements 12', by means of connecting lines 57. Lines 57 terminate in loops 64 which slidingly engage upper cable 52. A lower cable 54 is preferably threaded through coils 70 of the lowermost row of spring units and may be attached to draw lines in the manner well known to makers and users of purse seines.

When the compressed unit as shown in FIG. 5 is lowered over an object such as vehicle 80 and the bands 50' released, change of shape of the unit will cause the vehicle 80 to be ensnared as shown in FIG. 6.

FIG. 7 shows the type of spring module 12' useable in the exercise of the invention as shown in FIG. 5. Although the FIG. 2 and FIG. 7 springs are representative, it is to be understood that the spring loops and their configuration relative to each other are merely representative and may take any form consistent with the purpose for which they are to be used. Thus, if one loop or one connecting web member interferes with another web member or spring convolution it is a simple matter to relocate the web member with respect to another web member or to change the direction of convolutions in order to rectify the situation.

In FIG. 2, the spring units 12 have opposing convolutions 40 and 44 external of the enclosed loop and convolutions 38 and 42 extending internal to the enclosed loop a second modification is illustrated in FIG. 7.

Although only two practical embodiments have been shown with spring elements arranged orthogonally and cylindrically, respectively, it should be apparent that many other shapes and forms may be used to accomplish a variety of purposes without departing from the basic inventive concept disclosed.

What is claimed is:

1. A structure consisting entirely of a plurality of joined identical spring members; each said spring member consisting of a parallelogram of spring material having one or more convolutions at each apex; said spring members being joined together at the apices to form a structural pattern.

2. A collapsible and expandable structure consisting of a plurality of structural elements and means for fastening said elements together; each structural element consisting of an elongated endless spring member forming a quadrilateral; each said member having four sides or web portions intersecting in four apices; each of said portions being equal in length and being joined at the apices in one or more convolutions; said members being joined together by said fastening means only at the apices thereof in rows or tiers to form a structural pattern.

3. A modular construction element consisting of an endless length of spring material formed generally in the shape of a parallelogram with four side or web portions joined at four apices in one or more coils.

4. The element of claim 3 wherein one pair of opposing coils loops inwardly of said parallelogram

5. The element of claim 3 wherein all of said coils loop outwardly of said parallelogram.

6. A collapsible and expandable structure consisting of a plurality of structural elements and means for fastening said elements together; each structural element consisting of an elongated endless spring member forming a quadrilateral; each said member having four sides or web portions intersecting in four apices; each of said portions being equal in length and being joined at the apices in one or more convolutions; said members being joined together by said fastening means at the apices thereof in rows or tiers in circular array to form a cylindrical structural pattern.
